WEAVING IN LOOMS HAVING NIPPER SHUTTLES FOR DRAWING WEFT THREADS FROM STATIONARY SUPPLIES

Rudolf Rossmann, Gauting, near Munich, Germany, assignor to firm Tefag Textil-Finanz A. G., Zurich, Switzerland

Application May 23, 1933, Serial No. 672,390
In Germany May 23, 1932

5 Claims. (Cl. 139—126)

This invention relates to an improvement in or modification of the method and apparatus for weaving in looms having nipper shuttles as claimed in the U. S. patent application Ser. No. 482,323 according to which each weft thread, after being inserted in the shed, is cut off to a length somewhat greater than that required by the breadth of the fabric and the two thread ends projecting beyond the fabric are held on being cut off until they are beaten up by the reed and the shed is opened again, whereupon the said ends are bent into the next shed and beaten up with the succeeding weft thread.

During the bending-in of the free ends of the weft threads difficulties are liable to arise not only due to the formation of faulty sheds by reason of the fibrous surface or sizing of the warp threads causing these to adhere to each other, but in addition due to the thread ends of the weft tending to fray so that an unsightly pile may result in the finished selvedge.

According to the present invention each end of the weft thread is held by a clip arranged adjacent to the edge of the fabric and the end of the thread is drawn out of the clip as and when the ends are bent in. In this way the end of the thread is engaged by the clip until the bending-in operation is substantially complete.

In apparatus for carrying the invention into practice there may be associated with each clip a movable device which engages the weft thread while the latter is still held by the clip, and draws the thread from the clip and bends the thread into the shed. Each clip and the associated bending-in device are preferably constructed and relatively arranged so that as and when bending-in takes place the clip with the end of the weft thread in it enters or passes through an opening in the bending-in device and the latter then draws the thread out of the clip.

Conveniently the bending-in of each end of the weft thread is effected by a device having its operative part formed as a tube, eye or the like through or into which the clip can pass, said device being movable in the direction of the length of the weft thread and into the shed, when the clip holding the end of the weft thread will pass into or through the said tube or the like, which then engages the thread, inserts it into the shed and at the same time draws the end of the thread from the clip.

Alternatively each bending-in device may comprise a member in the form of a hook which is moved between the warp threads, first in an outward direction towards the edge of the fabric

where it engages the weft thread between the clip which holds it and the adjacent edge of the fabric, the hook returning and moving in the inward direction thereby drawing the weft thread into the shed and simultaneously drawing the end of the thread from the clip. 5

After insertion of each end of the weft thread into the shed, the ends of the thread are beaten up by the beating-up operation to which the succeeding weft thread is subjected. If desired however the bending-in could be effected during the formation of one of the succeeding sheds and the beating-up effected together with the next weft thread but one.

When the hooked type of bending-in device is employed the angle of the hook preferably lies in a plane parallel to the warp thread whilst each clip may hold an end portion of a weft thread so that this end portion is inclined to the main part of that thread which lies in the 20 shed. The hook will thus not tend to engage the warp threads as the bending-in device is moved during operation, whilst, in addition, the hook will readily engage the weft thread between the clip and the edge of the fabric. Each clip thus tends to give a slight twist to the weft thread so that the end of the weft is bent or forms a loop which can be readily engaged by the hook on the bending-in device. To facilitate such engagement each clip may be moved substantially parallel to the warp threads so that as the hooked portion of the bending-in device emerges from the shed the weft thread adjacent to the clip is engaged by the hook. 30

With a view to obviating the possibility of the hook portion on the bending-in device fouling or engaging the warp threads the part which carries the hook is enlarged adjacent to the hook in a direction transverse to the plane of the hook. During movement of the bending-in device through the warp therefore the warp threads are forced apart by the thickened part of the bending-in device and the hooked end can pass freely between the separated warp threads. If desired the hooked end of the bending-in device 45 may be furnished with a latch adapted to close the hook during the return or inward movement of the bending-in device, thereby obviating the possibility of a warp thread being engaged by the hook during the return movement of the bending- 50 in device.

The invention has the advantage that each cut-off end of the weft thread can be effectively bent into the shed since the clips situated adjacent to the selvedge prevent the thread from be- 55

coming disengaged from the bending-in device until the bending-in operation is complete. The bending-in operation is thus effected accurately so that the ends of each thread are perfectly anchored in the cloth and these ends cannot turn up to form a pile in the selvedge.

In the accompanying drawing

Fig. 1 is a diagrammatic showing of a modified bending-in mechanism with the bending-in finger in rest position.

Fig. 2 is a side view of the showing of Fig. 1 taken in the direction of the arrow on Fig. 1.

Fig. 3 is a diagrammatic showing of the bending-in mechanism as per Figs. 1 and 2 with the bending-in finger in the position it takes just before picking up the end of the thread to be bent in.

Fig. 4 is a side view of the showing of Fig. 3 taken in the direction of the arrow on Fig. 3.

Fig. 5 is a diagrammatic showing of the bending-in mechanism as per Figs. 1 and 2 with the bending-in finger in the position it takes just after picking up the thread end to be bent in.

Fig. 6 is a side view of the showing of Fig. 5.

Fig. 7 is a diagrammatic showing of the bending-in mechanism as per Figs. 1 and 2 with the bending-in finger in the position it takes just after picking up the thread end to be bent in.

Fig. 8 is a side view of the showing of Fig. 7.

Fig. 9 is a detail side view of the end of the finger used in connection with the mechanism illustrated by Figs. 1 to 8.

Fig. 10 is a top view of the finger-end illustrated by Fig. 9.

Fig. 11 is a detail side view of the finger-end used in connection with the mechanism illustrated by Figs. 1 to 8 and having a lock.

Fig. 12 is a top view of the showing of Fig. 11.

Fig. 13 is a diagrammatic showing of the clippers holding the weft thread and in open position.

Fig. 14 is a side view of the showing of Fig. 13.

Figures 1 to 8 inclusive illustrate an alternative arrangement of apparatus according to the invention. In this arrangement a clip *r'* is arranged adjacent to the edge of the cloth having clamping jaws *t_{1'}*, *t_{2'}* for engaging the end *a'* of a weft thread *a*, whereby the end of the thread within the jaws *t_{1'}*, *t_{2'}* lies in a direction at right angles to the length of the warp threads as clearly shown in Figure 2 which is a side view from left to right of the arrangement illustrated in Figure 1. The bending-in device comprises an operative portion *g'* carried on an arm *h'* pivoted on an axis *i'*, the free end of the portion *g'* being furnished with a hook *o* with the arm *h'* lying below the plane of the fabric.

When a weft thread has been inserted, beaten up by the reed *k* and engaged by the clip *r'* between the corresponding edge of the fabric and the point of weft supply, a slight twist is imparted to the end *a'* of the weft *a* due to the position of the jaws *t_{1'}* and *t_{2'}*, as shown in Figure 2. The weft thread is then cut off adjacent to the clip *r'* whereupon the reed *k* moves back and a new shed is formed. The arm *h'* is now rocked about the pivot *i'* in the counter-clockwise direction so that the hooked portion *g'* is moved in the outward direction, that is to say towards the edge of the fabric so as to pass between the warp threads indicated at *b'*, *b''* into the shed, as clearly shown in Figure 3, this forward movement of the bending-in device continuing until the hook *o* emerges adjacent to the clip *r'*. As the hooked end of the portion *g'*

emerges, the clip *r'* is moved towards the hook in a direction indicated by the arrow in Figure 3 and substantially parallel to the length of the fabric so that the end *a'* of the weft which lies between the edge of the fabric and the clip *r'* passes into the hook *o*, the end *a'* of the weft thread thus being looped about the end of the bending-in device *g'* as shown in Figure 4. At this operation some of the warp threads overlying *g'* are slightly distorted as, e. g., thread *a''* on Figure 4. The arm *h'* and operative portion *g'* of the bending-in device are now moved in the reverse or inward direction, i. e. from the edge of the fabric inwards, so that the end *a'* of the weft is pulled in the form of a loop into the shed, as shown in Figures 5 and 6, the end of the weft thread being at the same time drawn out of the clip *r'*. When the bending-in operation is complete, the jaws *t_{1'}* and *t_{2'}* are in the position shown in Figure 7, the succeeding weft thread is picked into the shed and beaten up by the reed *k*, this beating-up operation simultaneously beating the bent-in ends of the previous weft into the shed so that these are firmly anchored in position. It will be understood that the beating-up operation does not take place until the operative portion *g'* of the bending-in device has left the shed towards the end of its return or inward movement.

Figures 9 and 10 illustrate on an enlarged scale one form of the operative portion of the bending-in device of the type described with respect to Figures 1 to 8 inclusive. In the construction illustrated in Figures 9 and 10 the operative portion *g'* of the bending-in device is furnished on opposite sides with ribs *u'*, *u''*. The dimension of the portion *g'* as measured in a direction at right angles to the plane of the hook *o* decreases towards the hook, and when the hook *o* moves between the warp threads, these are held spaced apart by the ribs *u'*, *u''* a sufficient distance to allow the hook to pass between the warp threads without engaging them.

A further construction of the operative portion for the bending-in device is illustrated in Figures 11 and 12 in which a latch *v* is pivoted at *w* so that after the end of a weft thread has been engaged by the hook and the operative portion *g'* has commenced to move on its return on inward movement between the warp threads, the latch *v* closes over the hook which is thus prevented from engaging the warp threads. The latch *v* is however returned to its open position, that is to say clear of the hook, as soon as the hook again approaches the end of the next weft thread to be bent in.

I claim:

1. Mechanism for bending a weft thread over the edge of the fabric of which it forms a part and for weaving said weft thread into the warp threads of said fabric, said mechanism consisting substantially of a holder for holding said weft thread during the bending-in operation and a swingingly operated bending-in device having a hook for movement between the warp threads toward the edge of the fabric, engagement with said weft thread, reversal of the direction of movement and pulling said weft thread in between said warp threads and out of said holder.

2. Mechanism for bending a weft thread over the edge of the fabric of which it forms a part and for weaving said weft thread into the warp threads of said fabric, said mechanism consisting substantially of a holder adapted to hold said weft thread during the bending-in operation and

- a swingingly operated bending-in device having a hook for movement between the warp threads toward the edge of the fabric, engaging said weft threads, reversing the direction of movement and pulling said weft thread in between said warp threads and out of said holder, said bending-in device being, adjacent to the hook, and in a direction transverse to the plane of said hook, enlarged for the purpose set forth.
- 10 3. Mechanism for bending a weft thread over the edge of the fabric of which it forms a part and for weaving said weft thread into the warp threads of said fabric, said mechanism consisting substantially of a holder adapted to hold said weft
- 15 thread during the bending-in operation and a swingingly operated bending-in device having a hook for movement between the warp threads toward the edge of said fabric, engaging said weft thread, reversing the direction of movement and
- 20 pulling said weft thread in between said warp threads and out of said holder, said hook being

provided with a latch adapted to close said hook during the reverse movement of the bending-in device.

4. Mechanism for forming a selvedge by bending over a cut weft thread end and weaving it into the warp threads comprising movable means for holding the weft thread end and swinging bending-over means for pulling the weft thread in between the warp threads and out of said holder, substantially as described, as, and for, the purposes set forth. 10

5. Mechanism for forming a selvedge by bending over a cut weft thread end and weaving it into the warp threads comprising movable means for twistingly engaging and holding the weft thread end and bending-over means for pulling the weft thread in between the warp threads and out of said holder, substantially as described and as, and for, the purposes set forth. 15
